UNITED STATES PATENT OFFICE.

JACOB KLEINSCHMIDT, OF KIMMICK, MISSOURI.

VALVE GRINDER.

Application filed August 11, 1924. Serial No. 731,278.

To all whom it may concern:

Be it known that JACOB KLEINSCHMIDT, a citizen of the United States, residing at Kimmick, in the county of Jefferson and State of Missouri, has invented certain new and useful Improvements in Valve Grinders, of which the following is a specification.

This invention relates generally to valve grinders, but more particularly to the multiple stem valve grinders adaptable to the grinding of valves in removable cylinder heads and valve cages; and its object is to provide a valve grinding mechanism which will automatically oscillate, lift, reseat, and again oscillate the valves in their seats, until the said valves have been moved around their entire circumference and are properly ground tight.

Another object is to provide a simple practical and efficient device that can be operated either by hand or by power.

With these and other objects in mind the invention resides in its specific aspect in the construction, arrangement and operation of the several parts to be described in the accompanying drawings and specification.

In the drawings

Figure 1 is a side elevation of a valve grinding mechanism as mounted for use.

Figure 2 is a longitudinal vertical section.

Figure 3 is a transverse vertical section thru one of the valve grinding shafts.

Figure 4 is a transverse vertical section thru the gear housing and gears.

Figure 5 is a top plan view.

Figure 6 is a detail of one of the legs.

Figure 7 is a detail of an extension socket.

Figure 8 is a detail of the refacer.

In carrying out this invention, I provide a base 1 having base supporting legs 2 secured thereto. Tracks 3 are rigidly secured to the base 1 and are adapted to be releasably secured to the cylinder block by means of legs 4. A primary rack bar 5 having a shaft aperture 6 cut therein is slidably mounted upon the base 1. The said rack bar 5 has gear teeth 7 cut therein. A drive shaft 8 is vertically journaled in the base 1 and the gear housing 9 which is secured to the said base 1. A half gear 10 is mounted upon the vertical drive shaft 8 above the primary rack bar 5. Spur gears 11 are rotatively mounted upon shafts 12 journaled in the base 1 on both sides of the primary rack bar 5, and engage the gear teeth 7 of

the rack bars 5 and the half gear 10. A worm gear 12^a is rigidly secured upon the vertical drive shaft 8 and is adapted to enmesh a worm 13 mounted upon a shaft 14 horizontally journaled within the gear housing 9. The said shaft 14 has its one end squared as shown at 15 to permit operating the grinding mechanism either with a crank or with a motor. In the event a motor is used for operating the grinding mechanism, the base 1 is extended as shown in Fig. 4 to permit mounting the motor thereon. Shaft brackets 16 are releasably secured to the tracks 3. The said shaft brackets 16 have cam shaft apertures 17, cam apertures 18, grinding shaft apertures 19, pinion apertures 20, and rack bar apertures 21 provided therein. A beveled gear 22 is mounted upon the vertical drive shaft 8 above the half gear 10 and the worm gear 12^a. A beveled gear 23 which meshes with the beveled gear 22 is mounted upon a cam shaft 24 journaled in the gear housing 9 and in the cam shaft apertures 17 of the shaft 8 brackets 16. The said cam shaft 24 has a key way 25 cut therein for its entire length. Cams 26 having keyways 27 cut therein are slidably secured within the cam apertures 18 upon the cam shaft 24 by means of keys 28. The said cams 26 have concavo-convex peripheries as shown at 29. The keyways 27 of the cams 26 are cut at different angles for a purpose to be later explained.

Grinding shafts 30 having keyways 31 cut therein and spring caps 32 carrying coil springs 33 slidably secured thereto by means of set screws 34 which engage the said keyways 31, slidably engage the grinding shaft apertures 19. The said grinding shafts 30 have sockets 35 cut therein. Pinions 36 are slidably secured upon the grinding shafts 30 by means of keys 37 engaging the keyways 31. Coil springs 38 are mounted upon the grinding shafts 30 and engage the pinions 36 and the spring caps 32. A secondary rock bar 39 having gear teeth 40 cut therein is rigidly secured to the primary rack bar 5 and engages the rack bar apertures 21 and the pinions 36. Plates 41 having apertures 42 provided therein, are mounted over the grinding shafts 30 and secured to the shaft brackets 16. Valve engaging stems 43 are releasably secured in the sockets 35 of the grinding shafts 30 by means of thumb screws 44. Centering cups 45 and coil springs 46 are

mounted upon the valve engaging stems 43; the said coil springs 46 being adapted to engage the grinding shafts 30 and the centering cups 45. Extension 5 sockets 47 are provided, and adapted to engage the sockets 35 of the grinding shafts 30. One of the legs 4 is hinged as shown by the dotted lines in Fig. 6. Legs of various design may be employed to suit the design of 10 the various cylinder blocks. Refacing knives 48 are provided and when in use they are located between the valve seats and the valves. In operation the refacing knives 48 face off the valve seats when rotating in one 15 direction and the valves when rotating in the opposite direction.

In operation the tracks 3 are secured to the cylinder block by means of the legs 4 so that the centering cups 45 set over the 20 valves; the shaft brackets 16 and cams 26 being slidingly secured. The said centering cups 45 may readily be aligned with the valves without difficulty. The coil springs 46 which engage the grinding shafts 30 and 25 the centering cups 45, are adapted to keep the said centering cups 45 in constant engagement with the cylinder block. When the vertical drive shaft 8 is rotated, the beveled gear 22, which is mounted upon the 30 said vertical drive shaft 8, rotates the cam shaft 24 thru the medium of the beveled gear 23, while the half gear 10 which is also mounted upon the vertical drive shaft 8 operates the primary rack bar 5 carrying 35 the secondary rack bar 39, reciprocatingly thru the medium of the spur gears 11. The grinding shafts 30 are reciprocated thru the pinions 36 which are mounted upon the said grinding shafts 30 and mesh with the 40 secondary rack bar 39. The cams 26 are adapted to keep the valves firmly seated in the valve seats when grinding, while the concaved portions of the said cams 36 are provided to permit the coil springs 38 to raise

the said grinding shafts 30 for reseating the 45 valves. If it is desired to look at the valves during the grinding operation, the end legs 4 are released and the device laid over on its side, where it is held in that position by the 50 hinged leg 4.

While I have herein described a certain specific manner and method of constructing and assembling the elements of my invention, it is understood that I may vary from the same in minor details, not departing 55 from the spirit of my invention, so as best to construct a practical device for the purpose intended, as defined in the appended claim.

I claim:

In a device of the kind described comprising a base; base supporting legs secured to the base; tracks secured to the base; legs secured to the tracks for engaging the cylinder block; a primary rack bar having gear teeth and a shaft aperture provided therein slidingly mounted upon the base; a gear housing secured to the base; a drive shaft vertically journaled in the gear housing and in the base, engaging the shaft aperture provided in the primary rack bar; a half gear mounted upon the vertical drive shaft; spur gears rotatively secured to the base engaging the half gear and the primary rack bar; means for driving the vertical drive shaft, 75 shaft brackets, releasably secured to the tracks; grinding shafts mounted in the shaft brackets; pinions slidingly secured to the grinding shafts; a secondary rack bar having gear teeth cut therein, mounted in the shaft brackets, engaging the pinions secured to the primary rack bar; valve engaging stems secured to the grinding shafts; and means engaging the grinding shafts for seating and re-seating the said grinding shafts. 85

In testimony whereof I affix my signature.

JACOB KLEINSCHMIDT.
